UNITED STATES PATENT OFFICE.

PAUL SEITLINGER, OF MERIDEN, AND JAMES D. BERGEN, OF HARTFORD,
ASSIGNORS TO THE J. D. BERGEN COMPANY, OF MERIDEN, CONNECTICUT.

DESIGN FOR A GLASS VESSEL.

SPECIFICATION forming part of Design No. 24,127, dated March 19, 1895.

Application filed February 4, 1895. Serial No. 537,300. Term of patent 3½ years.

To all whom it may concern

Be it known that we, PAUL SEITLINGER, of Meriden, county of New Haven, and JAMES D. BERGEN, of Hartford, in the county of Hartford, State of Connecticut, have invented a new Design for Glass Vessels; and we do hereby declare the following, when taken in connection with the accompanying drawings and the letters of reference marked thereon, to be a full, clear, and exact description of the same, and which said drawings constitute part of this specification, and represent, in—

Figure 1, a plan view of the vessel; Fig. 2, a vertical central section thereof.

This invention relates to a design for the ornamentation of glass vessels, and the design consists in the configuration and ornamentation as shown in the accompanying illustrations.

As herein shown the design consists of an eight-pointed star radiating from the center of the under side of the bowl, the points of the star being separated from each other by a series of parallel grooves A A, having a rib

B, between them, the surface of which is corrugated, as at C, giving to the rib the appearance of a beading. The diamond-shaped spaces D between each pair of grooves A A and which form the points of the star, are filled by ray-like ornamentations, springing upward toward the upper edge of the bowl. The spaces between the points of the star are filled by a series of upwardly branching fans E, which form the upper configuration of the bowl, all as shown in the accompanying illustrations.

We claim—

The design for glass vessels, as herein shown and described.

In testimony whereof we have signed this specification in the presence of two subscribing witnesses.

PAUL SEITLINGER.
JAS. D. BERGEN.
